US00D790533S

(12) **United States Design Patent** (10) **Patent No.:** **US D790,533 S**
(45) **Date of Patent:** **** Jun. 27, 2017**

(54) **NOTEBOOK COMPUTER HOUSING**

(71) Applicant: **Google Inc.**, Mountain View, CA (US)

(72) Inventor: **Yoshimichi Matsuoka**, Sunnyvale, CA (US)

(73) Assignee: **Google Inc.**, Mountain View, CA (US)

(**) Term: **15 Years**

(21) Appl. No.: **29/547,020**

(22) Filed: **Nov. 30, 2015**

Related U.S. Application Data

(60) Division of application No. 29/485,664, filed on Mar. 21, 2014, now Pat. No. Des. 750,615, which is a division of application No. 29/468,269, filed on Sep. 27, 2013, now Pat. No. Des. 719,149, which is a continuation-in-part of application No. 29/448,147, filed on Mar. 11, 2013, now Pat. No. Des. 702,225, and a continuation-in-part of application No. 29/447,980, filed on Mar. 8, 2013, now Pat. No. Des. 711,368, and a continuation-in-part of application (Continued)

CLAIM

The ornamental design for a notebook computer housing, as shown and described.

DESCRIPTION

FIG. 1 is a front perspective view of a notebook computer housing according to my design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

Broken lines are environmental only and form no part of the claimed design.

1 Claim, 7 Drawing Sheets
